UNITED STATES PATENT OFFICE.

SOLOMON K. HINDLEY, OF WORCESTER, MASSACHUSETTS.

BOOT OR SHOE.

SPECIFICATION forming part of Letters Patent No. 268,892, dated December 12, 1882.

Application filed September 19, 1882. (No model.) Patented in England May 17, 1882, No. 2,325.

To all whom it may concern:

Be it known that I, SOLOMON K. HINDLEY, of Worcester, in the county of Worcester and State of Massachusetts, have invented a certain new and useful Improvement in Boots or Shoes, of which the following is a specification.

My invention relates to that class of boots or shoes known as "stitch-down" goods, in which the upper is turned outward upon a sole, a welt placed upon the outwardly-turned portion of the upper, and the welt and upper united to one or more soles by a row or rows of fastenings outside of the body of the upper.

In goods of this class as hitherto made the outward-turned edge of the upper has been made to extend flush with the sole-edge, forming a part of the finished edge; but inasmuch as upper-leather usually contains more oil than sole-leather, if it is allowed to form a part of the sole-edge when it is stained and burnished in the process of finishing, it will not be of the same color as the welt above and the sole beneath it. Furthermore, if the goods are kept in store, the oil is apt to exude from the edge of the upper-leather, and thus injure the appearance of the shoe. The unfinished appearance of the sole-edge will be more marked when a cloth upper is used.

My invention consists in cutting off the outward-turned portion of the upper a short distance back from the intended line of the finished sole-edge, so that the edge of the upper shall be covered by the superposed welt, the edge of the finished boot or shoe being made up of the welt and the edges of the out-soles.

My invention is herein described and shown as applied to a boot or shoe in which one or more waxed-thread seams are used to unite the welt and upper to a sole or soles; but it will be obvious that rows of fastenings of other material may be used.

The accompanying drawings, in which similar letters of reference indicate like parts, represent vertical sections across the ball of stitch-down boots or shoes, in which the upper sur-

face and edge of the outwardly-turned portion of the upper are covered by a superposed welt.

The welt may be single or double, and the seam or seams outside of the body of the upper may be arranged in any of the ways shown in the drawings and herein described, or in other ways, without departing from this invention, so long as the outwardly-turned portion of the upper is covered by a superposed welt or its equivalent.

Figure 1 is a vertical section across the ball of a shoe, in which the outward-turned portion of the upper is chamfered off a short distance back of the edge of the upper sole. A is the upper; B, the sole; C, a welt covering the upper surface and edge of the outwardly-turned portion of the upper; E, a seam uniting the welt, the outwardly-turned portion of the upper and the sole; G, an insole.

In Figs. 2, 3, and 4 the outwardly-turned portion of the upper is chamfered off and covered by a welt in each case. In Fig. 2 the upper is fastened to the upper sole, B, by a seam, F, and the superposed welt and one or more soles are united by another seam, E, outside of the former seam. In Fig. 3 both seams pass through and appear on the surface of the welt. In Fig. 4 the outwardly-turned portion of the upper is covered by a folded welt, and the seams are arranged as described in Letters Patent No. 262,592, dated August 15, 1882, granted to me.

The process of manufacture of this improved boot or shoe does not differ from that employed in making stitch-down boots or shoes, in which a welt is used above and resting upon the outwardly-turned portion of the upper, except that before the welt is stitched on the edge of the upper must be cut back or chamfered off. The welt also should be beveled, as is shown in the drawings, so that its upper surface may be in substantially the same plane with upper surface of the insole G.

It is preferable to chamfer off the outwardly-turned edge of the upper rather than to groove out the welt, as might be done, because the welt can thus be held more firmly

down in contact with the sole and the uniformity of the sole-edge better preserved.

I claim—

An improved boot or shoe having its upper turned outward upon an upper sole and united thereto by a seam or row of fastenings outside the body of the upper, the outwardly-turned portion of the upper being chamfered off a short distance back of the sole-edge, and

having, also, a welt covering the chamfered surface and edge of the outwardly-turned portion of the upper, substantially as and for the purpose set forth.

SOLOMON K. HINDLEY.
